HARRY CADWALLADER, JR., OF PHILADELPHIA, PENNSYLVANIA.

MACHINE-CLAMP.

1,376,077.

Specification of Letters Patent. Patented Apr. 26, 1921.

Application filed March 13, 1919. Serial No. 282,453.

To all whom it may concern:

Be it known that I, HARRY CADWALLADER, Jr., a citizen of the United States, and a resident of Philadelphia, county of Philadelphia, State of Pennsylvania, have invented certain new and useful Improvements in Machine-Clamps, of which the following is a specification.

Some of the objects of the present invention are to provide a clamp for machine shop practice to hold a piece of work in fixed position upon a planer, a lathe, drill press, milling and boring machines and other suitable supports; to provide a clamp whereby machine work can be set up in a minimum time; to provide a clamp arranged to direct the applied force substantially perpendicular to the face of the work engaged by the clamp; to provide a clamp arranged to co-act with work material which is not provided with lugs or flanges capable of being engaged by a clamp; and to provide other improvements as will hereinafter appear.

In the accompanying drawings Figure 1 represents a side elevation of an end clamp embodying one form of the present invention; Fig. 2 represents a bottom plan of the same; Fig. 3 represents a side elevation of 30 a modified form of the invention; Fig. 4 represents a bottom plan of the same; Fig. 5 represents a side elevation of another form of the invention; Fig. 6 represents a bottom plan of the same; and Figs. 7, 8 and 35 9 represent respectively operative positions of the several clamps.

Referring to the drawings one form of the present invention consists, as shown in Figs. 1 and 2, of a body 10 formed of suitable material designed to withstand bending, shearing or other stresses and strains and generally of a character to stand up under the rough use of a machine shop.

For the purpose of distributing the various strains to which the clamp is subjected in use, and giving essential strength with a minimum of material, the body 10 is provided with a base 11 of substantially uniform thickness, two opposite side edges of 45 which are formed with substantially perpendicular flanges 12 to give depth of body where needed to prevent bending or shearing. The outer edges of these flanges 12 are rearwardly tapered as indicated at 13 and 50 merge into side extensions 14 of a rear wall 15, these latter members providing a plane

surface 16 at the rear of the body 10 which forms a substantial seat to support that end of the clamp upon a table, block or any suitable support.

For clamping the piece, part or any work to be held securely to the machine table, the body 10 is provided with a laterally disposed jaw 20 formed substantially as a continuation of the base 11, the top surface of 60 the jaw 20 being, preferably, beveled to form a relatively thin gripping edge adapted to seat in slots or openings of small dimensions with which the work may be provided. A slot 21 is formed through the 65 base 11 in axial coincidence with the long axis of the body 10, this slot being relatively long and of a width to receive the shank of a bolt 22 by means of which the body 10 is made fast to the supporting 70 table to hold the work in fixed position. By thus providing a slot lengthwise of the body 10 and of considerable length, free adjustment of the clamping bolt 22 can be had and the work may if desired be removed 75 80 without entirely disconnecting the bolt 22 from the body 10.

As a means to grip the work, and also to prevent movement of the work during the clamping action, the jaw 20 is provided with 85 a projection 23, preferably extending transversely of the jaw and presenting a rounded bearing surface for contact with the work face upon which it is to seat. This feature of the clamp is an important one in that it 90 directs the applied force substantially perpendicularly to the work surface whatever the angular position of the clamp body relative to the work. Where a plane clamping face is employed and the clamp is below and 95 angularly positioned with respect to the work, the applied force acts at such an angle as to push or force the work away from the clamp so that in operation the part held works loose and the entire set-up has to be 100 done over. With the rounded or beaded lip formation on the jaw this difficulty is overcome and the work is clamped fast under all normal angular positions of the clamp.

In Figs. 3 and 4 another form of the invention is shown wherein the clamp body 10 is of the double end type, each end being similar in construction to the jaw 20 shown in Fig. 1. The body in this modified form is provided with two opposite, parallel, side 110 flanges 24 for strengthening purposes and between which a slot 25 of elongated con-

figuration is located in the body for the passage of the bolt 22. The jaws 26 are respectively provided with transverse, rounded work engaging projections 27, the function of which is the same as that herefore explained.

In Figs. 5 and 6 another form of the invention is shown wherein the rounded gripping jaw construction is applied to a flat 10 clamp of the bifurcated type for use, more particularly, in the clamping of work which does not have lugs, flanges or other projecting parts readily engageable by a clamp of the single or double end type. In this form 15 the legs 30 are respectively provided with rounded projections 31 on the jaws 32, while the body 33 of the clamp has a lug or stem 34 arranged to serve as a support for one end of the clamp. The legs 30 are spaced 20 sufficiently to provide a recess 35 to receive the shank of the clamping bolt 22 and to permit proper adjustment as will be understood. Where the work to be clamped has no projecting ledges, lugs or flanges adapted 25 to form a seat for one end of a clamp, a small hole can be drilled at a convenient point in the side of the work and the stem 34 inserted, after which, the free ends being 30 suitably supported upon blocks, the clamp may be tightened and the work thus firmly held.

In Figs. 7, 8 and 9 the several forms of the clamps forming the present invention are shown in operative position engaging, holding 35 and clamping a part to be machined in fixed position upon a machine table. The entire arrangement is simple and effective, the clamps are readily applied to any class of work and can be adjusted to any height 40 or position by using the ordinary packing

blocks in the shop, and when in position will stand all the normal strains and stresses without bending or breaking.

Having now described my invention, what I claim is:—

1. In a clamp for machine work, a body part having a longitudinally disposed slot therein, a jaw formed on one end of said body and extending laterally therefrom, a rounded projection formed on one side of said jaw to contact with work to be clamped, a pair of flanges formed respectively at opposite edges of said body and extending in the same direction as said rounded projection, said flanges having a depth greater than the thickness of said jaw and respectively merging into one face of said jaw, and means between said flanges and traversing said slot for clamping said body and jaw to hold said work. 55

2. In a clamp for machine work, a body part having a longitudinally disposed slot therein, jaws formed respectively on the ends of said body part and extending in opposite directions laterally therefrom, a rounded projection formed on one side of each jaw to contact with work to be clamped, said projections projecting in the same direction, a pair of flanges formed respectively at opposite edges of said body part and extending in the same direction as said projections, said flanges having a depth greater than the thickness of the respective jaws, and means between said flanges and traversing said slot for clamping said body and jaws to hold said work. 70

Signed at Philadelphia, in the county of Philadelphia, and State of Pennsylvania, this 10th day of March A. D. 1919.

HARRY CADWALLADER, JR.
